(57) **CLAIM**

The ornamental design for a mountable anchor point, as shown and described.

DESCRIPTION

FIG. 1 is a front perspective view of the mountable anchor point;

FIG. 2 is a right side view of the anchoring device as shown at FIG. 1.

FIG. 3 is a left side view of the anchoring device as shown at FIG. 1.

FIG. 4 is a bottom view of the anchoring device as shown at FIG. 1.

FIG. 5 is a top view of the anchoring device as shown at FIG. 1.

FIG. 6 is a back view of the anchoring device as shown at FIG. 1; and,

FIG. 7 is a front view of the anchoring device as shown at FIG. 1.

The broken lines represent portions of the structure or environment that form no part of the claim.
